J. T. EVANS, JR

INSTANTANEOUS STARTER

Filed Jan. 16, 1923

Fig. 1.

Patented Dec. 16, 1924.

1,519,370

UNITED STATES PATENT OFFICE.

JOHN THOMAS EVANS, JR., OF BROOKLYN, NEW YORK.

INSTANTANEOUS STARTER.

Application filed January 16, 1923. Serial No. 613,075.

To all whom it may concern:

Be it known that I, JOHN THOMAS EVANS, Jr., a citizen of the United States, residing at 220 88th Street, Brooklyn, in the county of 5 Kings and State of New York, have invented a new and useful Instantaneous Starter, of which the following is a specification.

My invention relates to a new device for rapidly vaporizing cold gasoline as contained in carbureters when the motor is in 10 a condition commonly termed "cold."

This invention is constructed with the object of eliminating the usual difficulty of starting gasoline motors, particularly in cold 15 weather. It is also made with the object of reducing carbon deposits in the motor to an appreciable extent, and to absolutely prevent dilution of the crank case oil which dilution is brought about by introducing raw 20 gasoline into the cylinders by means of the "choke rod" the use of which is at present positively necessary to accomplish a reasonably quick and sure start. A further object 25 of this invention is to provide a simple yet efficient device for the purpose in view, which will be reasonably low in the cost of manufacture, and which can be easily adapted to installation on any of the present makes of 30 American motor cars. The device herein described and illustrated is intended to fit a model 490 Chevrolet touring car, but can by changes (when necessary) later described be made to fit other motor cars.

With the above and other objects in view, 35 the invention will now be described with reference to the accompanying drawing which illustrates the preferred embodiment of the same.

In the drawing:

40 Fig. 1 is a perspective view of the device with parts shown in dotted lines and parts omitted for the sake of clearness;

Fig. 2 is a top plan view of the device showing parts not shown by Fig. 1 and omitting other parts to avoid confusion;

Fig. 3 is a side view partly in section and elevation of the valve and ignition controlling device;

Fig. 4 is a sectional detail view.

50 Referring to Figure 1, the object drawn represents in the main a cylinder of approximately five and one half inches in diameter enclosed at both ends with metallic plates and having a steel tube of one and one half 55 inches diameter inserted in the center, the ends of which protrude from each end-plate

for a distance of one half inch. Number 17 indicates the cylinder itself. Numbers 15 and 16 the end plates which are drawn tightly against the ends of the cylinder by means 60 of two bolts marked 18. Directly in the center of the cylinder and the two end plates is inserted a steel tube of one and one half inches diameter and approximately one thirty-second of an inch thick. This tube 65 is indicated by number 2. Attached to both ends of this tube are two elbows marked 22 and 23. Attached to the end of these elbows are two short pieces of tube (one quarter of an inch protruding from each 70 elbow) marked 4 and 5 each pierced with a hole marked 7 and 8. All leading makes of motor cars are equipped with a "stove" which is a metallic shell encircling the exhaust pipe. The air used in carburation is 75 drawn thru this stove and conveyed to the carbureter by means of flexible steel tubing. After the motor has been in operation for at least five minutes, the exhaust pipe becomes very hot, and as a consequence the air 80 drawn in thru the "stove" becomes thoroughly heated. This hot air when it reaches the carbureter and comes in contact with the raw gasoline contained therein, causes such gasoline to vaporize or become volatile 85 instantly, thus aiding materially in forming the correct gaseous substance which produces perfect combustion within the motor. However, when the motor is left standing 90 inoperative for any length of time, it cools off, 90 and when we attempt to operate it again, we have no hot exhaust pipe to heat the air stuck in around the "stove." As a consequence we resort to the "choke rod" which by its action excludes a great deal of the air 95 from the carbureter, and naturally only raw drops of gasoline are drawn into the firing chamber. These do not explode readily if at all and are instrumental in forming most of the carbon found in all gasoline motors. 100 It also seeps down past the piston rings and dilutes the lubricating oil in the crankcase. In time some of this raw gasoline will become ignited and the motor will start functioning, not however as it should. 105 There will be considerable "misfiring" and uneven operation until the exhaust pipe becomes hot enough to warm the air being drawn in thru the stove. This invention is intended to supply the hot air when the 110 motor is cooled off or in a condition commonly termed "cold."

Referring back to the description of the device itself the flexible steel tubing leading from the "stove" is to fit snugly over parts marked 4 and 5 which will bring hole 9 on flexible steel tubing in line with holes 7 and 8, when bolt 6 may then be inserted to accomplish a union of the parts in question.

While passing thru tube marked 2 (Fig. 1) the air is thoroughly heated to approximately 180 degrees Fahrenheit in ten to fifteen seconds by means of nine burners each marked 10^a which utilize for any suitable fuel. This fuel is conveyed to the burners thru three pipes each marked 11. These pipes are connected at the upper end as indicated in Figure 2 by means of elbows marked 12 and T's marked 13. With further reference to Figure 2, object marked 14 represents a valve of the conventional type used to control the entrance of the gas into the device. Object marked 14^b represents a strong spiral spring secured to some convenient anchorage to keep the valve in an "off" position when flexible cable 14^a is not pulled in an opposite direction which direction is indicated by arrow.

Referring back to Figure 1, the burner tips 10^a are simply small steel tubes made of nonoxidizing steel and threaded at one end for connecting them to feed pipes 11. Attached to outer cylinder 17 are pipes of one and one-quarter inches diameter placed as indicated by numerals 20 and 21, which are used to convey air to the inside of said cylinder. Flexible steel tubing of a sufficient size is connected to the ends of said pipe in the same manner as described above with reference to parts marked 4 and 5. These sections of flexible tubing connected to pipes 20 and 21 are of a length sufficient to reach for at least eight feet to some underneath outside part of the car. This is a precautionary measure to insure absolute safety when the burners are functioning. The oxygen so necessary to fire will be drawn from a source where there will be no danger of contamination with fumes of gasoline or other inflammable substances.

With further reference to Figure 1, number 19 indicates a threaded hole cut in cylinder 17 which will be of a size sufficient to accommodate a standard half inch spark plug which shall be instrumental in igniting the gas issuing from the burner tips.

I will now refer to Figure 3 which represents the controller of the device previously described. Number 24 indicates a metallic plate of approximately three inches width and four inches depth. Each corner of said plate shall be cut with a countersunk hole to accommodate a bolt such as marked by numbers 25 and 26 the purpose of which bolts is to attach said plate to the instrument board of an automobile. It will be necessary to cut a hole in the instrument board

approximately two and three quarters by three and three-quarter inches in size so as to accommodate the parts attached to the back of plate 24. Numeral 27 refers to a nickel plated round metallic knob attached to rod 28 for the purpose of being easily grasped by a human hand. Rod 28 is to be approximately three inches in length and will project thru a hole of sufficient diameter which shall be cut in the center of plate 24.

A pin shall be inserted thru rod 28 as indicated by number 29. Directly behind pin 29 shall be a metal washer number 32 which shall slide freely on rod 28. This washer will be of a diameter sufficient to insure its coming in contact with points marked 30 and 31 when knob 27 is grasped and pulled away from plate 24. Directly behind above described washer shall be a coil spring as indicated by number 38 which shall be retained on rod 28 by washer 33 and pin 34. The purpose of this spring is to hold in absolute contact with points 30 and 31 larger washer number 32 when rod 28 is pulled out thru plate 24. This will make the electrical contact to produce a spark at the points of the spark plug inside cylinder 17 (Fig. 1) said spark plug being screwed into hole 19 (Fig. 1). When rod 28 is pulled out thru plate 24 it will not only cause the electrical contact above described, but will also "open" valve 14 (Fig. 2) when a cable such as indicated by 14^a (Fig. 2) is suitably connected to the valve handle as illustrated and connected to hole 35 on rod 28 (Fig. 3). This arrangement of parts will automatically perform two operations at once. It will turn on the gas or fuel and at the same time produce a spark to ignite the fuel thus producing the results desired. A further point of value is the fact that the device only functions so long as the individual or operator knowingly keeps rod 28 withdrawn from its socket. As soon as the operator's hold is released, spring 14^b (Fig. 2) pulls rod 28 (Fig. 3) back into its socket at the same time pulling valve 14 (Fig. 2) to an "off" position and drawing washer 32 (Fig. 3) away from contact points 30 and 31, thus the device ceases to function.

Referring back to Figure 3, numbers 40 and 41 indicate two circular pieces of insulating material such as hard rubber or compressed fibre. A hole shall be countersunk in the center of one end as illustrated to accommodate a bolt of sufficient size, said bolts indicated by numbers 30 and 31. Under the nut of each of these bolts can be secured the wires used in making the electrical connections to produce the spark at the spark plug points. These pieces of insulating material referred to above are attached to plate 24 by small bolts marked 42 and 43 which are set in countersunk holes cut in plate 24 as illustrated. Number 46 refers to a light coil

spring the purpose of which is to keep knob 27 pressed firmly against plate 24 to prevent rod 28 from rattling in its socket.

Figure 4 is an enlarged view illustrating 5 the manner in which pipes 11 (Fig. 1) are passed thru end-plate 15 (Fig. 1). A hole of a diameter slightly larger than pipe 11 (Fig. 4) is cut in plate 15. The upper ends of pipe 11 are threaded to accommodate lock- 10 nuts 51 and 52. To firmly affix pipes 11 to plate 15 simply place same thru hole indicated by number 53 and tighten lock-nuts 51 and 52.

While I have shown and described the 15 preferred specific embodiment of the invention, it will be understood, in view of my disclosure, that the invention is capable of other embodiments and that certain changes in the 20 construction and arrangement of parts to accommodate the device to the various types of automobiles may be made without departing from the invention as defined by the appended claims.

I claim:

25 1. A heating device for combustion engines comprising means forming a heating chamber, a conduit passing therethrough, a normally closed valve for controlling the passage of gas to said chamber, ignition means

in said chamber, and means for opening said 30 valve and operating said ignition means at substantially the same time.

2. A heating device for combustion engines comprising a conduit for the passage of fluid to the engine, means for conducting gas for 35 heating the fluid passing through said conduit, a valve for controlling the passage of gas through said gas conducting means, means for igniting said gas, and a single device for controlling the operation of said 40 valve and said gas igniting means.

3. A heating device for combustion engines comprising means forming a heating chamber, a conduit passing through said chamber, 45 means for conducting air to said chamber, means for conducting combustible gases to said chamber, electric ignition means, means in said chamber for igniting the gases therein, a normally closed valve for controlling the passage of gases to said chamber, 50 means for opening said valve, and means associated with said valve opening means for closing an electric circuit through said ignition means while the valve is opened and for opening the electric circuit when the 55 valve is closed.

JOHN THOMAS EVANS, JR.
